Attorney

UNITED STATES PATENT OFFICE

JOHN GALLAGHER, OF PHILADELPHIA, PENNSYLVANIA

ADVERTISING DEVICE

Application filed May 14, 1930. Serial No. 452,224.

The object of the invention is to provide improvements in advertising devices and particularly in those of the active or animated types.

Another object is to provide a frame with means to oscillate the same, such as a wave-actuated or motor-driven device, and both audible and visual means carried thereby to attract and hold the attention of persons while advertising facts are presented to them.

A further object is to provide in such a device visual means, consisting of rotatable members which are intermittently propelled so as to continuously rotate, thereby producing a much different effect than would be the case if the members remained stationary.

Still another object is to provide in the device audible means, which whirl about their respective axes, and are provided with reeds adapted to emit predetermined tones, while concave extensions of the said means operate to drive air currents through said reeds, and when said reeds are of different tones to produce a musical chord.

And a still further object consists in providing a construction which adapts the device to being mounted as upon the end of a pier or wharf, so that the movement of the waves therebeneath will operate to drive the device both as a whole and as to its individual elements, without the consumption of other energy.

With these and other objects in mind, the present invention comprises further details of construction and operation, which are fully brought out in the following description, when read in conjunction with the accompanying drawings, in which Fig. 1 is a front elevation of the device, partly in section; Fig. 2 is a fragmentary portion of the float used in the same; Fig. 3 is an enlarged diametrical section of one of the sound-producing elements; Fig. 4 is a front elevation of the same, with a portion broken away; and Fig. 5 is a central vertical section of the device as illustrated in Fig. 1.

Referring to the drawings, any suitable support is represented by a pier comprising a platform 1, supported by spaced piles 2,

and having an extension 3 provided with a slot 4. From the under side of said platform, or its extension, there extends a bracket 5, to which is pivotally connected a diagonally downwardly extending radius rod 6, to the lower end of which is pivotally connected at 7 a bar 8, which is rigidly secured to any desired and suitable form of float 9, which normally rests upon and rises and falls with the surface of the water 10. To the upper end of the bar 8 there is pivotally connected a rod 11, the upper end portion of which passes through the slot 4 in the pier extension 3, and is pivotally connected at 12 in any suitable manner to the outer free end 13 of an oscillatory member 14, which is pivotally mounted at 15 with respect to the pier platform 1, the opposite end 16 of the member 14 being adapted to support an adjustable weight 17 which counteracts the dead weight of the float 9 and rods 6 and 11 upon the first-mentioned end of said oscillatory member.

To the rear of the pier platform is secured the base portion 18 of a segmental bracket 19, which is provided adjacent to its outer periphery with radially spaced bosses 20 and 21, through which extend axial bores 22. Nearer to the center of said bracket there is also provided a boss 23, through which also extends an axial bore 22. Secured to the oscillatory member 14 and extending upwardly therefrom are preferably two radially spaced racks 24 and 25, which extend in parallel planes, said first rack being provided with outwardly directed teeth 24^a and with inwardly directed teeth 24^b, while the smaller of said racks is provided with outwardly extending teeth 25^a.

Extending through each of the bores 22 in the bosses 20, 21 and 23 is a tubular shaft 26, upon its rear threaded end being provided with nuts 27, while its forward end is provided with a flange 28, which with said nuts predetermined the axial position of the shaft. Beyond said flange each shaft comprises a threaded end portion 29, to which is secured the central internally threaded portion 30 of a hollow bell-shaped member 31, which is preferably made of a suitable resonant

metal and serves not only to set up sound vibrations, as hereinafter described, but by reason of its substantially conical shape being operative to amplify such sound vibrations after having been initially set up. The 5 free end portion 29 of said shaft within said bell-shaped member is provided with a suitable fixture 32 which supports an electric lamp 33.

10 The freely extending periphery of said member is also provided with a suitable member 34, which operates to support a gauze or fabric 35, which extends across the otherwise open end of said member and is adapted 15 to screen the interior thereof, while permitting sound and light to pass freely therefrom. The sides of said member are provided with apertures 36, across which are mounted any desired number, shape, and arrangement of 20 tuned reeds 37, or other form of wind-operated sound-producing elements, while adjacent to each of said apertures the material of said member is pressed outwardly therefrom, as clearly shown in Fig. 4, to form means for 25 deflecting air currents radially inwardly through said apertures and past said reeds or their equivalent. Thus, as each of said members is rotated at high speeds, it emits a sound, tone, or musical chord which is predetermined 30 by the characteristics of the respective reeds or other musical tone-producing elements.

Each of the tubular shafts 26 also extends through a shield 38, which if desired may be ornamented, and which screens that portion 35 of the device to the rear of the sound-producing bell-shaped members first described. Additionally, each of said shafts rotatably carries a gear 39, which meshes with either the teeth 24^a or 24^b upon said rack 24, while 40 each of said gears is connected through a ratchet 40 with the shaft upon which it is mounted.

With this construction, it will be obvious 45 from the drawings that as the rack 24 oscillates to-and-fro, the series of members 31 upon its outer side will continue to rotate in uniform counterclockwise direction, while those of said members upon the radially inner side of said rack will continue to rotate in 50 clockwise direction, as viewed in Fig. 1. Thus, with various color or figure characteristics of the gauzes 35 covering said sound-producing members, a very attractive effect 55 may be produced as one series of members rotates in one direction, while the other series rotates in the opposite direction closely adjacent to the first.

In addition to the foregoing bell-shaped 60 members, a hollow conical member 41, spanned by a transparent or partially transparent closure 42, and containing an electric lamp 43, is secured to the outer free end portion of the single tubular shaft 44, which carries a gear 45 in mesh with the smaller rack 65 25. As this member will rotate first in one

direction and then in the other, and usually at slower speeds than those of the two sound-producing series of elements, it is not thought necessary to depend upon it for the production of sound, but instead to reserve for it merely the function of presenting an oscillatory surface for any desired advertising or other indicia.

The uppermost marginal portion of the shield 38 may be provided with cutout letters 70 46, covered by a colored glass or other medium 47, to the rear of which are positioned electric lamps 48. These lamps may be enclosed within a protective housing 49, from the rear of which depends a wall 50, which 75 serves to shield the rear of the device from dust, dirt, and foreign particles of any sort, including water or spray. This last-named wall may be provided with a normally covered aperture 51, through which is accessible, when desired, any well-known form of electric distribution or flash mechanism 52, into which leads wires 53 from a suitable source of current, and from which lead various wires 54 to the lamps 33, 43, and 48.

Having thus described my invention, what I claim and desire to protect by Letters Patent of the United States is:—

1. A device of the class described, comprising an oscillatable member, a segmental rack carried thereby and centering about the axis of oscillation, a rotatable element, a gear and ratchet unit connecting said element to said rack, and means carried by said element to produce sound as it rotates.

2. A device of the class described, comprising an oscillatable member, a segmental rack carried thereby and centering about the axis of oscillation, a rotatable bell-shaped element, a gear and ratchet unit connecting said element to said rack, and reeds carried by said element to produce sound as said element rotates with the oscillation of said member.

3. A device of the class described, comprising an oscillatable member, a pivotal support therefor, a rack conforming to a segment of a circle and concentric with said pivot, a relatively fixed support, rotatable elements carried by said fixed support, gear and ratchet units connecting said elements to said rack, to transform the intermittently reversing motion of said rack into uni-directional rotations of said elements, and means carried by said elements to create sound while rotating.

4. A device of the class described, comprising an oscillatable member, a pivotal support therefor, a rack conforming to a segment of a circle and concentric with said pivot, said rack having teeth facing in opposite directions, a relatively fixed support, series of rotatable elements carried by said fixed support, gear and ratchet units connecting one series of said elements to one,

set of rack teeth and similar units connecting the other series of said elements to the opposite set of rack teeth, to transform the intermittently reversing motion of said rack 5 into uni-directional rotation of the elements of said series in opposite directions.

5. In a device of the class described, a rotatable support, a circular hollow member carried thereby and having an aperture, 10 sound-producing means within said member and adapted to be operated by air currents passing through said aperture, and means outside of said member to deflect said currents towards and through said aperture to 15 actuate said first means.

6. In a device of the class described, a rotatable support, a hollow bell-shaped sound-amplifying member carried thereby and having an aperture, the larger end of 20 said member being substantially unobstructed, and sound-producing means within said member and adapted to be operated by air currents passing radially inwardly through said aperture.

25 7. In a device of the class described, a rotatable support, a bell-shaped sound-amplifying member carried thereby and having an aperture, sound-producing means adapted to be operated by air currents passing through said aperture, and a flared portion of said member adjacent to said aperture being operative to deflect said currents towards and through said aperture.

30 8. In a device of the class described, a rotatable support, a bell-shaped sound-amplifying member carried thereby and having a plurality of apertures, and sound-producing means of different tone characteristics adapted to be operated by air currents passing 35 through said apertures, to produce and to amplify on said member to amplify a musical chord.

In testimony whereof I have affixed my signature.

45 JOHN GALLAGHER.
